(57) **CLAIM**

Related U.S. Application Data

The ornamental design for a top of a glove box for a personal
watercraft, as shown and described.

(62) Division of application No. 29/128,818, filed on Sep. 1,
2000.

DESCRIPTION

(51) **LOC (7) Cl. 12-06**

The FIGURE is a top plan view of a glove box for a personal
watercraft showing our new design, the broken line showing
of environmental structure is for illustrative purposes only
and forms no part of the claimed design.
